UNITED STATES PATENT OFFICE.

FRANK W. DARLING, OF NEW YORK, N. Y., ASSIGNOR TO THE L. A. THOMPSON SCENIC RAILWAY COMPANY, OF NEW YORK, N. Y., A CORPORATION OF NEW JERSEY.

COASTER FOR CHILDREN.

Application filed January 8, 1926. Serial No. 79,983.

My invention consists in a roller coaster loop planned and constructed in such manner that very small children may have a close simulation of sled coasting over an 5 irregular curved slope with the maximum of exciting sensations continued with such perfect safety that they need not be accompanied by adults, but can be left to freely make use of the coaster unattended.

10 The invention involves principles of dimensioning and correlating the elevations, gradients, curvatures and other characteristics of the loop to effect this purpose of providing maximum safety with elimination 15 of danger of injury to small children for whom the coaster is especially constructed. Practically such a coaster loop should be of considerable length, not only that a substantial coast can be had, but also in order that 20 there shall be a variety of sensations felt by the child.

In one sense, the novel roller coaster loop involving my invention gives in lesser degree sensations similar to the standard gravity rides constructed for adult use, but the 25 problem of devising a child's coaster presents difficulties not experienced in the design and construction of such adult gravity rides, and necessitates a special novel construction and correlation to effect the purpose intended.

For example, my novel coaster loop is of a character to be used solely by very small children,—even as young as four years of 35 age, and accordingly in addition to the requisite of absolute safety, the coaster sensations must be of a comparatively mild character with correspondingly low velocities and accelerations and deceleration rates. 40 For example, where in adult gravity rides speeds of from 40 to 50 miles or greater are permissible, it is important in a children's coaster of the character herein set forth that the coaster cars shall have maximum speeds 45 far below such permissible speeds for adult gravity railways, with accompanying substantially smaller ranges in speed variations, but though the speed must be greatly reduced it is desirable to give the rider the 50 illusion of great speed. In the actual installation upon which this application is based, the maximum speed at any point is not greater than 15-16 miles per hour, the average speed being, of course, substantially 55 lower than this, and the acceleration or de-

celeration and centrifugal force effects throughout the coaster and measured in percentages of weight are milder than similar permissible effects in adult gravity rides, but the illusion of high speed is obtained by 60 utilizing cars of very small size and light weight, by incorporating in the coaster a special construction of successive hills and valleys to give rapidly succeeding and alternating accelerations and decelerations, and 65 by a special construction of coaster track so that there are no upright projections in line with the eyes of the children passengers. Due to these comparatively low velocities and acceleration rates and on account of the 70 special degree of safety demanded, a special coaster construction is essential to effect the required continuous non-stalling coasts about the loop under all service conditions, with the repeated accelerations and decel- 75 erations closely following each other so as to obtain a maximum number of such sensations on a given length of coaster, and the problem is further complicated by the necessity for inexpensive installations making 80 use of very light cars and permitting profitable nickel rides.

To the above ends, I have devised a coaster loop consisting of a succession of gradual inclines alternating with simulated structural 85 hills and I have so correlated the average gradients, radii of curvature of the hills and valleys measured vertically, and the slopes or track inclinations on leaving the structural hill crests, with a given specially constructed 90 light weight conveyance which is utilized, so as to give coasting sensations to the exact degree and quantity desired, and to effect the continuous non-stalling rides notwithstanding the lightness in weight of the cars 95 and low speeds thereof. For example, the maximum gradient and drop at any point and the average gradient, or the average speed, ordinarily should be chosen so that the loss of weight or acceleration effect due 100 to linear acceleration at such point must not exceed 50% of the total weight of the conveyance and the children passengers, and preferably substantially less, this acceleration effect being measured by the formula: 105

$$= (W \cos \theta - f) \cos \theta, \text{ where}$$

W is total weight of conveyance and its passenger load,
f is total friction ($fw + fb$) due to bearings and wind,

110

θ is angle between tangent to coaster way at point in question and vertical through the same point.

In the particular installation upon which this application is based, I utilize a four traction-wheel ball bearing conveyance weighing not more than 150 pounds when loaded and approximately four feet in length, and I have found that in order to secure the safe non-stalling continuous coasting sensation rides desired the average gradient throughout the greater portion of the loop should not be substantially less than 1 to 30 and may be as great as 1 to 22½, together with average maximum gradients of the steepest inclines which are not substantially greater than 1 to 4 and with maximum actual drop at any one dip of from one-third to one-half of the total net drop from the highest point to the lower point of the coaster, these figures being based on an actual installation of a loop whose effective gravity coaster ride is approximately 300 feet long and includes seven structural hills and valleys. The structural hills or crests must also be so correlated with the gradients as to avoid a combined acceleration and centrifugal force effect at any point which would be sufficiently violent or pronounced to frighten or tax the nerve strength of children of the tender age for whom this coaster is adapted, and this consideration requires that the radius of the curvature measured vertically of any structural valley must not be less than a predetermined minimum, depending among other things upon the gradient and the speed down the dip. The centrifugal force effect at any point

$$= \frac{WV^2}{gr} \cos \theta_1$$

where

W is total weight of conveyance and passenger load

g is gravitational constant (32.2)

V is velocity along track

r is radius of curvature of track at point in question, and

θ_1 is angle between line connecting point on track and center of curvature and vertical through center of curvature.

It is also important that the coaster be of a character that may be constructed and installed at a minimum cost and which also requires a minimum of attention in operation and my invention is directed to an actual installation which, in practice, has met all of the requirements of a coaster adapted for children of kindergarten age and which, on account of the novel features of construction and operation embodied therein, and on account of the comparatively low installation and operation cost may be profitably operated on a nickel ride basis.

For a better understanding of my inven-

tion, reference may be had to the accompanying drawings forming a part of this application wherein—

Figs. 1 and 2 are diagrammatic views illustrating the general plan of my new 70 coaster,

Fig. 3 is a transverse sectional view of the track showing a kiddie's car mounted thereon,

Fig. 4 is a side elevation and general outline of the car and track,

Fig. 5 is a plan view thereof, and

Figs. 6 and 7 are diagrammatic views illustrating certain general principles upon which my coaster is based.

Referring to the drawings wherein like numerals designate similar parts throughout, Fig. 1 indicates generally the vertical elevations and drops of the track, the curve A indicating the gravity coaster ride upon which the cars B are adapted to travel of their own weight and momentum after having once been conveyed to the highest point by the conveyor C, this conveyor connecting the ends 1 and 5 of the effective gravity coaster ride so as to carry the cars from the lowest point 1 to the highest point 5 and to impart the initial speed or velocity to the cars B before the beginning of the first descent or drop D of the track.

In the particular embodiment shown the coaster is indicated as having beginning with the first drop or dip D and including the starting platform J, a total of seven drops or dips, and, of course, an equal number of structural hills corresponding thereto. For convenience I have successively designated the dips as D, E, F, G, H, I and J. Also, according to this embodiment, the loop is in the form of a continuous structure with elongated sides K, K', and connecting end structures L and M, the part M being a gradual curve and leading to the lowest point 1 of the track while the end part L is substantially straight but has curved parts merging into the adjacent ends of the side branches K, K' of the track.

The track structure A includes a bedding or supporting framework of vertical posts 50 and girders 51, upon which are mounted the traction rails 52. The latter are in the form of timbers which overhang the side rails 53, thereby extending into the chute or well 54 formed between the tracks. The traction rails 52 may be of any convenient material to use such as wood, and, if desired, may be provided with metallic traction surfaces 52'. The car B includes four small traction wheels 55 journaled underneath the sides thereof with a seat 57 of the car substantially on a level with or slightly above the axis of the wheels. The car is provided with a downwardly extending passenger compartment 57' which extends down to points approximating the bottom of the

chute between the rails, and is provided with side guide wheels 58, these latter being adapted to engage the side rails 53 on going around curves and to frictionlessly steer the car along the traction rails 52, 52'. The traction rails 52 overhang these side guide wheels 58 and prevent the accidental displacement of the car from the traction rails. The car is of very light weight and in the particular installation upon which this application is based the weight of the car with its children load therein is not substantially greater than 150 pounds. By reason, however, of the particular construction of the car with the passenger compartment extending down into the chute or well between the traction rails the stability of the car is assured at all times, even when going around curves, and ordinarily in normal operation the car adheres to the traction rails and the side wheels 58 or their brackets do not engage the overhanging edges thereof.

I have found that with a range of speeds of from four or five to fifteen or sixteen miles per hour a coaster may be constructed to give a variety of hill-valley coasting sensations which approach and simulate those experienced on natural hills, and moreover with entire freedom from the dangers incident to coasting in the open spaces. Moreover, I effect a particular correlation of gradients, dips and radii of curvature measured vertically which insure the continuous uninterrupted running of the cars throughout the coaster way, notwithstanding the low speeds and velocities thereof, while the coasting sensations are maintained within prescribed and predetermined limits and harmless at all times. The particular construction of coaster way and structural hill and valley for effecting these purposes is indicated diagrammatically in Figs. 6 and 7. In Fig. 6 the curve corresponds to the effective gravity ride portion of the coaster, namely, that portion between the point where the car leaves the elevator C and that point where they are engaged by the elevator, and in this diagram the vertical distances correspond to the actual drop while the horizontal distances correspond to the length of the coaster way. For convenience in exposition, the vertical drops are on a larger scale than the horizontal distances or lengths and in the particular embodiment illustrated the relative scale is 9 to 1. The line N, O indicates the average gradient for the effective part of the gravity ride, this gradient corresponding generally to a drop of 1 in 30, while the line N, P indicates the gradient from the highest point of the coaster to the lowest point, and this corresponds generally to a drop of 1 in 22. The distance between the highest point N of the coaster and the lowest point P thereof is approximately three-fourths of the effective gravity ride. That portion of the

gravity ride having the more pronounced coasting sensations is that part of the coaster way designated K', a series of three closely successive dips being included in this part of the coaster, and the gradient line R, P between the highest point in this section and the lowest point thereof corresponding approximately to 1 in 17. The gradient N, O is observed to approach a line joining the crests of the structural hills, the latter at 75 the beginning falling slightly below the line N, O but towards the end rising slightly above this gradient. In the particular embodiment illustrated, the steepest grade of a dip occurs between the points S and T and 80 the average gradient between these two points is approximately 1 in 4. The construction is such that the maximum speed of the cars at the bottoms of the dips range from 10 to 15 miles per hour, depending 85 upon the speed at the crest, the drop and the gradient, with a given car, while the speeds at the crests vary from four miles at N, the highest point of the coaster, to eight miles per hour, depending upon the particular correlation of gradients, drops, etc., immediately preceding the crest. The coasting sensations do not depend so much upon the actual velocity at any point as upon the deceleration, acceleration and centrifugal effects, and both the linear acceleration or deceleration and the centrifugal force effects must be taken into account in the construction of the coaster. Since the centrifugal force and the linear acceleration effects are 100 added together on the dips, the latter particularly must be constructed with such gradients, actual drops and curvatures that the combined sensations due to these two different forces may be kept within the permissible 105 prescribed limits. I have indicated in Fig. 7 on an approximately correct and enlarged scale that portion of the coaster including the dip H. The centrifugal force effect at any point, as indicated above, is 110 given by the formula:

$$\frac{WV^2}{gr} \times \cos \theta_1$$

while the linear acceleration or deceleration 115 effect is measured by the formula:

$$(W \cos \theta_1 - f) \cos \theta_1$$

I have found that with an accelerating speed down the dip up to a maximum of 120 fifteen miles per hour at the bottom of the dip the radius of curvature r should not be less than approximately twenty feet to insure the moderate and harmless sensation for the small children concerned. In the 125 particular embodiment illustrated where the speed of the cars at the crest S is approximately eight miles per hour and with a total drop of the succeeding dip H, slightly less than five feet over a longitudinal distance 130

of eighteen feet, the radius of curvature may be safely as low as 20 feet, and the coaster between the points S and V is constructed on these principles. Similarly the 5 radius of curvature of the dip between the points R and S and other dips where the velocity and acceleration approach these limits should not be substantially less than twenty feet, and in the particular installation upon which this application is based, the radii of curvature of the other dips measured vertically are arranged above 20 feet (the radius for the dip H), the greatest 10 combined acceleration, deceleration and centrifugal effects of the present embodiment 15 being experienced in dip H.

With this construction of coaster wherein the gradients, actual drops and radii of curvature measured vertically are taken into account and correlated along the general 20 lines and principles indicated, an artificial coaster way is provided wherein children of tender age may safely be left alone to travel as passengers in the coaster car with assurance 25 that they will obtain continuous coaster sensations with entire safety and without undue violence. The cars once they are launched from the conveyor or elevator C proceed by gravity and the initial momentum imparted thereto to traverse the coaster way, descending the grades and ascending the structural hills with certainty and with variations in speed and course indicated to give the coaster sensations desired.

Having thus described my invention, what I claim and desire to protect by Letters Patent is:

1. A gravity coaster loop structure for small children whose effective gravity ride has an average gradient from one end to the other of not less than 1 in 30 and not greater than 1 in 20 and including a succession of structural hills and valleys of varying lengths, gradients and vertical curvatures, the structure of any portion of said loop and an immediately succeeding structural valley being such that the combined acceleration and centrifugal force effects upon a car at any point within said immediately succeeding valley shall not be greater than that determined by a maximum velocity down said valley of sixteen miles per hour, with a radius of curvature of twenty feet of the valley.

2. A gravity coaster loop structure for small children whose effective gravity ride

portion has an average gradient of not less than 1 in 30 and not greater than 1 in 20 and including a succession of structural hills and valleys of varying lengths, gradients 60 and curvatures, the structure of any portion of said effective gravity ride part and an immediately succeeding structural valley being such that the combined acceleration and centrifugal force effects of a car at any 65 point within said immediately succeeding structural valley is not greater than that determined by a maximum speed of eight miles per hour on the immediately preceding crest, an approximate actual drop of 70 five feet down said valley with an average gradient of approximately 1 in 4 and a radius of curvature measured vertically of said valley of approximately twenty feet.

3. A gravity coaster loop as set forth in 75 claim 1, wherein each succeeding structural hill is approximately at an elevation corresponding to the average gradient line for the entire effective portion of the loop.

4. A gravity coaster loop of the character 80 set forth in claim 1 wherein the tangents to the crests of the structural hills approximate an average gradient line of 1 in 30.

5. A gravity coaster loop structure whose effective gravity ride portion has an average 85 gradient of approximately 1 in 30, and including a succession of descents and ascents of varying lengths and gradients, the maximum average descending gradient for any descent being not substantially greater 90 than 1 in 4 with an actual drop of not substantially greater than five feet whereby such sensations of coasting with a sled down an irregular hill are created under conditions to combine exciting sensations for children with complete safety.

6. A closed gravity coaster loop with elongated sides including a succession of structural hills and valleys of varying lengths, gradients and curvatures in which the average 100 gradient throughout the effective gravity ride portion including the bends is approximately one in thirty, with gradients progressively increasing for smaller portions of the loop to a maximum of one in four 105 for the steepest hill and with a radius of curvature of any hill measured vertically not less than 20 feet.

In testimony whereof, I have signed my name to this specification.

FRANK W. DARLING.
